UNITED STATES PATENT OFFICE.

EDWIN H. MESSITER, OF BROOKLYN, NEW YORK.

VIBRATORY ACTUATOR.

1,252,826.

Specification of Letters Patent.

Patented Jan. 8, 1918.

Application filed August 15, 1914. Serial No. 856,917.

To all whom it may concern:

Be it known that I, EDWIN H. MESSITER, a citizen of the United States of America, and a resident of Brooklyn, Kings county, 5 and State of New York, have invented certain new and useful Improvements in Vibratory Actuators, of which the following is a specification, reference being had to the accompanying drawings, forming a part 10 thereof.

My invention relates to vibratory means for producing a rotative movement and has for one of its objects to provide an electro-responsive oscillatory actuator that shall be 15 adapted to effect a step by step rotative movement of a driven member.

A further object is to provide a device of the aforesaid character that shall be equipped with a simple and reliable circuit controller 20 for governing the energization of the electro-responsive actuator.

Other objects and advantages of my invention will be set forth hereinafter, and in order that my invention may be thoroughly understood, I will now proceed to describe the same in the following specification and then point out the novel features thereof in appended claims.

Referring to the drawings:

30 Figure 1 is an elevation of a mechanism embodying my invention.

A part of the same mechanism is shown in its opposite position in Fig. 2.

The device illustrated comprises an oscillatory member pivotally mounted at 10 and comprising an arm 11 to which is secured a circuit controller 12 and an armature 13, and an arm 14, which is fashioned to produce a double pawl structure comprising fingers 15 and 16.

The armature 13 is located between a pair of stationary magnets 18 and 19 having core members 20 and 21.

25 is a star wheel mounted on a shaft 26 45 to which any suitable driven member may be secured such as for example, a set of counters for an integrating meter (not shown).

Each of the fingers 15 and 16 has an end 50 22 and a shoulder 23 which are so positioned and proportioned relative to each other and to the center of the shaft 26 as to engage the teeth 27 of the star wheel 25.

Assuming that the magnet 19 is first energized so that it attracts the armature 13 to the position shown in Fig. 1 the shoulder

23 of finger 16 will engage one of the teeth 27, moving the star wheel and its connected parts, until the end 22 of the same finger engages another of the fingers 27 and thereby acts as a stop to prevent further rotation of the wheel.

If the magnet 18 is now energized and the magnet 19 de-energized, the armature will swing in the opposite direction, moving the arm 14 into the position shown in Fig. 2. The end 22 of the finger 15 now acts upon the star wheel moving it in the same direction of rotation as indicated by arrow 30, until a tooth comes into engagement with the shoulder 23 of the finger 15. The teeth 27 are arranged and proportioned to co-operate with the double pawl in the manner described. The finger and shoulders of the pawl are so shaped and arranged that their driving engagement with the teeth of the star wheel is nearly a straight push with a minimum slip, and the stopping engagement is direct and positive.

The circuit controller 12 comprises a bulb 80 or tube of glass or other insulating material which is substantially horizontal when the arm 11 is midway between the ends of its swing and is provided near its respective ends with sets of contacts 31 and 32 and 85 contains a small quantity of mercury or other conducting fluid. When the arm is oscillated into the position shown in Fig. 1, the contacts 31 are disconnected while the mercury or other conducting fluid in the 90 tube interconnects the terminals 32. When the mechanism occupies the position shown in Fig. 2 the contacts 31 are connected instead of the contacts 32.

By connecting the contacts 31 in a circuit 95 35 of the magnet 19 and the contacts 32 in a circuit 36 of the magnet 18, as shown diagrammatically in Fig. 1, the circuits will be completed in alternation and the bell crank lever oscillated so as to produce a step 100 movement of the star wheel.

This application is a continuation in part of my copending application Serial No. 784,342 filed August 12, 1913, and assigned to Electric Weighing Company.

105

What I claim is:

1. A vibratory actuator comprising in combination, a driven star wheel, a bell crank lever comprising a double pawl near the outer end of one arm of the lever, an armature near the outer end of the other arm of the lever, electro-magnets on opposite sides

- of the armature, and control means on the bell crank lever and adapted to alternately energize the electro-magnets to oscillate the pawl.
- 5 2. A vibratory actuator comprising in combination, a driven star wheel, a bell crank lever comprising a vertical arm, an armature therefor, a contact-carrying tube extending transversely of the vertical arm 10 conducting liquid in the tube adapted to selectively engage the contacts, stationary magnets adapted to oppositely influence the armature, and a pawl arm fashioned to provide a pair of fingers disposed on opposite 15 sides of the star wheel, each of said fingers having an actuating projection and a stop projection.
3. A vibratory actuator comprising in combination, a driven star wheel, an actuating pawl therefor, an oscillating arm connected with and depending vertically from the pawl, an armature therefor, a contact-carrying tube extending transversely of the arm, conducting liquid in the tube adapted to selectively engage the contacts, and stationary magnets adapted to oppositely influence the armature. 20 25

In witness whereof I have hereunto set my hand in the presence of two subscribing witnesses, this 13 day of August, 1914.

EDWIN H. MESSITER.
